UNITED STATES PATENT OFFICE.

ALEXANDER F. WINTERS AND BASIL R. CRAMPTON, OF GRAND RAPIDS, MICHIGAN.

REVERSIBLE LATCH.

Application filed July 22, 1926. Serial No. 124,230.

This invention relates to latches and is concerned with a reversible latch which may be used on doors swinging either to the right or to the left. This is of particular value in the matter of refrigerator latches, though it is also of value for latches in other relations such as kitchen cabinets and the like. The hardware for refrigerators, cabinets and like articles is normally manufactured by establishments equipped for that purpose and sold to the refrigerator or cabinet manufacturers. Orders are placed for a certain number of each kind of latch, that is, for "rights" or "lefts" and it is, of course, the intention that there shall always be a sufficient supply of each kind on hand to keep the production schedule going. At times, however, it is found that latches of the one kind are exhausted while possibly many thousands of the other kind will be on hand.

The present invention makes it possible to not only manufacture both "right" and "left" latches with one set of dies, all of the parts which enter into the latch being formed the same whether the latch is of one type or the other, but it is also possible for the refrigerator or cabinet manufacturer, in case the supply of one type of latch should be exhausted, to very readily change latches of one type which are on hand to the other. That is, a right hand latch may be changed to a left hand, or vice versa with very little trouble and this will be done rather than have the production schedule stopped.

It is a primary object and purpose of the present invention to produce a latch of the character described capable, merely by different assembly of the parts, of being made either a right hand or a left hand type of latch; and also capable of being very readily changed from one type to the other. A further object of the invention is to provide in a latch of such character additional means whereby the latch when attached to a door and the door opened will be held in disengaged or retracted position until the door is closed, whereupon it is automatically tripped so that the latch lever engages automatically with a keeper for holding the door closed; and this will occur irrespective of which type of latch may be used, that is, either a right hand or a left hand latch. A still further object of the invention is to produce a latch of this character and having the capabilities stated in a very simple and economical manner, all parts of the latch

being formed from sheet metal by means of dies and being very simply and easily assembled.

For an understanding of the invention by means of which these results are attained reference may be had to the following description taken in connection with the accompanying drawings, in which

Fig. 1 is a fragmentary front elevation of a refrigerator door and casing having a latch and keeper applied thereto respectively, the latch casing being shown in section for a better disclosure of the interior structure.

Fig. 2 is a horizontal section through the door and keeper substantially on the plane of line 2-2 of Fig. 1.

Fig. 3 is an elevation and vertical section substantially on the plane of line 3-3 of Fig. 1, the door being in partly open position.

Fig. 4 is an enlarged transverse section through the latch lever prior to the permanent securing thereto of a rocker member 80 with which the latch spring is engaged.

Fig. 5 is a similar view after said rocker member has been permanently secured.

Fig. 6 is an under plan view of the latch.

Fig. 7 is a fragmentary section through said latch on the plane of line 7-7 of Fig. 6.

Fig. 8 is a section through the latch substantially on the plane of line 8-8 of Fig. 6, the spring being removed, and

Fig. 9 is a perspective view of the parts 90 of a disassembled latch, the parts thereof being separated and shown in a position inverted from that which they occupy when in use.

Like reference characters refer to like 95 parts in the several views of the drawings.

The door 1 to which the latch is applied may be a door of any suitable article of furniture, such as a refrigerator. The latch includes a covering of sheet metal having an intermediate raised housing 2 from which ears 3 extend in opposite directions through which screw fastenings may be passed to attach the housing and the parts assembled therewith securely to the door 1. In opposite ends of the housing openings 4 and 5 are made, as best shown in Figs. 1 and 9. Against the upper side of said housing 2 a bar 6 of flat metal is positioned having short end portions 7 turned at right angles with which tongues 8 engage to securely hold the bar in place. A pin 9 of sheet metal is

attached at one end to the bar 6 and extends therefrom at right angles at its free end being formed with two fingers 9^a which may be turned outwardly, as will later appear, to 5 secure the base plate in place.

Through the housing described a latch bar, with an integral handle for operating the same, may be passed. The latch bar and handle are formed from a single piece of 10 sheet metal making the handle 10 from which the bar extends, said bar being of channel form including a web 11 and spaced apart flanges 12, which at the free end of the bar are rounded inwardly toward each other 15 making a keeper engaging end 13 of the form shown in Fig. 9. This latch bar or lever with the integral handle 10 is pivotally mounted on the pin 9, previously described, a relatively large opening 14 being made 20 through the web 11 for the passage of the pin.

A short distance from the opening 14 each of the flanges 12 is formed with a slot or recess 15. A rocker member 16 of sheet 25 metal is designed to be permanently attached to the latch lever and for this purpose it is made with a rectangular opening so as to pass freely over the lever whereby a cross bar 16^a of the member 16 is brought directly in 30 alignment with the slots 15 and may then be forced downwardly into said slots and into the channel between the flanges 12, as indicated at 16^b in Fig. 5, this making a very 35 secure and rigid connection of the rocker member to the latch bar. Said rocker member at each end and a short distance outward from each flange 12 of the lever is turned at right angles and formed into an arm 17. Each arm 17 terminates in a projection 18 40 at its free end and is formed with oppositely extending lugs 19 and 19^a, the former of which is located a greater distance from the free end of the projection 18 than is the latter.

45 A coiled spring 20 is designed to be placed at one end over the projection 18 so as to bear against the shoulder of the lug 19^a but by reason of the position of the lug 19 it will not bear against its shoulder in the same 50 manner that it does against that of the lug 19^a. This is fully shown in Fig. 2. The outer end of the spring 20 engages with a sheet metal abutment which is located in the 55 opening 4 of the housing at one side of the latch lever.

The sheet metal abutment includes a section 21 from which a second section 22 is turned at right angles, this terminating in a short lip 23 turned at right angles so as to 60 lie in a plane parallel to the plane of the section 21. At the opposite end of the section 21 the metal is bent inwardly and then back upon itself, as indicated at 24, terminating in a tongue 25 which lies a distance 65 from and in parallel relation to the section

22 described. It is over the tongue 25 that the other end of the coiled spring 20 is placed. The invert portion 24 of the abutment is located back of the end of the housing 2 between the lip 7 on bar 6 at said end 70 of the housing and the adjacent side of the housing partly filling the opening 4 and lying in the same plane with said end of the housing (see Fig. 2). It is held in this position at the opposite end of said member by 75 the base plate which closes the inner side of the housing and the construction of which will now be described.

The base plate 26 is a plate of sheet metal 80 and has two elongated openings 27 cut there-through symmetrical with the transverse center line of the plate. These openings are of the same width as the lip 23 so that said lip 85 may be received therein, as shown in Fig. 2, and hold the sheet metal member described 90 against outward movement from pressure exerted by the spring 20. The plate also at what may be termed its front edge has a shelf 28 of triangular shape turned back 95 upon it, having sides 29 coming together at the point of the shelf, as shown in dotted lines in Fig. 6. The plate also at the same edge is formed with tongues 30 pressed inwardly so as to engage with the notches 30^a 100 made at opposite edges of the opening 4 in the latch casing, as best shown in Fig. 9. When thus engaged a circular opening 31 in the plate may be brought over the pin 9 and the retaining fingers 9^a on the free end 105 of the pin are then turned outwardly, as shown in Fig. 6, so as to securely hold the plate in position. Of course, when the latch is attached to a door and the screws are passed through the ears 3 and the base plate underneath them there is no possibility of 110 detachment of the base plate.

The abutment including the parts 21 to 25 inclusive, as described, may be placed at either side of the latch lever and the spring 20 may be placed so as to engage with the lug 18 at the free end of either arm 17. Such change in position of the abutment member against which the spring engages with the corresponding change in position of the spring causes the latch to be reversed, 115 that is, changed from either a "right" to a "left" or vice versa. The spring 20 and the abutment can be very readily disengaged and detached through one opening 27 and reassembled on the opposite side of the latch lever through the other opening 27. Should a refrigerator or cabinet manufacturer find that the supply on hand of latches of one type was exhausted while it still had on hand a great many of the other type, such latches of the other type or as many of them as may be needed can be very quickly 120 changed so as to supply the necessary latches of both types or kinds. This is a very desirable and valuable feature of our invention. 125 130

In addition, the possibility of making the latches of either type or kind with the same tools and dies is of great value. The manufacturing process in the factory does not have to be changed so far as fabricating the various parts is concerned. All that is necessary is to reverse the position of the spring and the abutment against which it bears at its outer end to change from one type of latch to the other and this can be very readily taken care of in the assembly department where, after a certain quantity of latches of one type have been assembled then the assembly is changed to make a desired quantity of latches of the reverse type.

With a latch of this character when the latch lever is swung about its pivot beyond the shelf 28 it will engage with an edge 29 of said shelf to hold the lever in retracted position, this appearing in dotted lines in Fig. 1. This is caused by reason of the fact that the opening 14 is enough larger than the diameter of the pin 9 that the lever may rock on the pivot due to the combined effect of the outward pull on the handle 10 and the force of the spring 20 whose line of force is from the center line of the tongue 25 to the shoulder of the lug 19^a against which the spring bears at its opposite end, thereby causing a tendency of the lever to tilt or rock about the pin 9 causing it to engage with an edge 29 of the shelf 28 when retracted far enough that it may pass by such edge. Upward movement of the lever on the pin 9 is prevented by the lugs 19. When the lever is freed from the shelf it returns to normal central position as shown in Fig. 1, being stopped in such position by engagement against an edge of the abutment described. When the abutment member is changed to the opposite side and the spring is likewise changed, the lever may swing in the opposite direction and will, when swung far enough, engage with the opposite edge 29 of the shelf 28.

The keeper which is attached to the door casing or jam 32 includes a base 33 from which a post 34 projects outwardly terminating in a head 35 which, with the post, forms a hook-like keeper having an outer cam side 26 and an inner inclined side 37. The end 13 of the lever, when the door is closed and when it is engaged with the keeper, bears against said inclined inner side 37 and acts to wedge the door tightly to closed position. A trip finger 38 extends from the base 33 a short distance above the recess of the keeper and is in the position such that when the lever on the door held in retained and retracted position, as shown in dotted lines in Fig. 1, comes against the finger, it will dislodge said lever from the retaining shelf and free it so that it may engage with the keeper under the force of the spring 20. The keeper is also of a form

such that it can be used with doors swinging either to the right or to the left.

It is apparent from the foregoing that we have devised a simple, practical and economical form of door retaining latch which is reversible so that it may be used for either right or left hand swinging doors. It is also evident that the latch is very quickly changed from one type to the other even after it has once been assembled into supposedly permanent form. The possibility of manufacturing the latch of either type with the same tools and dies and the capability of the latch whereby it may be changed from one to the other and at the same time incorporate therewith the latch lever retaining and tripping features so that strains on the latch fastenings and door hinges are eliminated when the door is closed, all combine to make this latch one of great value. The invention is defined in the appended claims and is to be considered comprehensive of all forms of structure coming within their scope.

We claim:

1. A latch comprising a housing, a latch lever extending through the housing and pivotally mounted between its ends within said housing, a rocking member attached to said latch lever transversely thereof, said rocking member having an arm at each end spaced from and paralleling the length of the lever, an abutment detachably located at one end of the housing and at one side of the lever in substantial alignment with one of said arms of the rocking member, said abutment being adapted to be placed at either side of the lever and interchanged from one side to the other, and a coiled spring disposed between the abutment and the arm of the rocking member at the side of the lever at which the abutment is located.

2. In a latch, a housing having openings in opposite ends, a latch lever extending through the housing, a pivot pin attached to the housing and passing through the latch lever between the ends thereof, a rocking member permanently secured to and located transversely of the latching lever, an abutment located at one end of the housing and closing the opening at said end at one side of the latch lever, said abutment being adapted to be positioned at either side of the latch lever, and a coiled spring between said abutment and the rocking member, said spring paralleling and lying to one side of the latch lever.

3. A latch comprising a housing having open ends and an open inner side, a base plate closing the inner side of the housing, a pivot pin carried by said housing and extending through the base plate, a latch lever pivotally mounted between its ends on said pin, a rocking member connected to the lever and located transversely thereof, said mem-

ber extending to each side of the lever, an abutment located between the housing and base plate at one side of the lever and at one of the open ends of the housing and closing 5 said open end at one side of the lever, and a coiled spring under compression located between the abutment and one end of the rocking member, said coiled spring and abutment being readily changed from one side of the 10 lever to the other so as to engage said spring with either end of the rocking member.

4. A construction containing the elements in combination defined in claim 3, said base plate having a shelf located at its inner side 15 adjacent said abutment, said shelf being of triangular form and coming to a point a distance inward from the open end of the housing where the abutment is located.

5. In a latch, a sheet metal housing having 20 open ends, a bar secured in the upper portion of the housing lengthwise thereof, a hollow pivot pin connected to the bar, a base plate closing the inner end of the housing through which the pivot pin passes, said 25 pivot pin at its free end being formed with fingers adapted to be bent outward so as to hold the base plate in place with respect to the housing, a latch lever extending through the housing and pivotally mounted between 30 its ends on the pivot pin, and spring means engaging with the latch lever tending to turn it about the pivot pin in one direction.

6. In a construction of the class described, a housing having open ends, a pivot pin 35 connected with the housing and located within the same, a base plate closing the inner side of the housing, said base plate having two elongated openings therein, a latch lever extending through the housing above the 40 base plate and pivotally mounted on said pivot pin, said latch lever lying between said openings, an abutment having one end seated at one end of one of said openings and its other end engaged against an end of the 45 housing and closing one of the ends of the housing at one side of the lever, a rocker member connected to the lever and disposed transversely thereof, and a coiled spring under compression disposed between one end 50 of the rocker member and said abutment to hold the abutment in place by spring pressure and causing the lever to turn until it engages against the inner edge of said abutment, said spring and abutment being readily detached and removed through the opening in the base plate over which the spring 55 is located and replaced through the other opening in said base plate at the other side of the latch lever to engage the spring with 60 the other end of said rocker member.

7. In combination, a housing having an open inner side, a base plate closing said inner side of the housing, a latch lever extending through the housing, a pivot pin disposed 65 between the housing and base plate on which

the latch lever is pivotally mounted, a compression spring, means for selectively engaging the spring with the latch lever at either side thereof whereby the lever will be turned by said spring in reverse directions, and means for automatically retaining the lever in retracted position when moved against the compression of said spring irrespective of which side of the lever the spring is located. 70

8. In a latch, a sheet metal housing having an opening at each end and an open inner side, a bar of metal located in the housing lengthwise thereof at each end having a lip turned at right angles, tongues stuck from the housing at the open ends thereof extending across and engaging with notches in said lips to permanently secure the bar in the housing, a hollow cylindrical pin connected with and extending at right angles 75 from said bar, a latch lever pivotally mounted between its ends on said pin, a base plate closing the inner open side of the housing and having an opening for the passage of the free end of the pin, spring means acting on the lever to turn it in one direction, and fingers on said free end of the pin adapted to be bent outwardly to hold the base plate in place on the housing. 80

9. A latch lever comprising a housing having open ends and an open inner side, a base plate closing the open inner side of the housing, said base plate having two parallel elongated openings therethrough, a pivot pin carried by the housing and passing through said base plate, a latch lever pivotally mounted on said pivot pin, a rocker member connected to and located transversely of the lever, a sheet metal abutment located at one side of the latch lever at one of the open ends of the housing closing the opening at said side of the latch lever, said abutment having a lip engaging in one of the openings in the base plate at one end and at its opposite end having a projection bearing against the inner side of the end of the housing above the opening at said open end thereof, and a coiled spring located between one end of the rocker member and said abutment releasably holding said abutment in place and turning the latch lever to engage against the edge of the abutment, said coiled spring and abutment being detachable from the lever and the housing in which they are located and removable through the opening in the base plate over which the spring is located and replaceable in the housing through the other opening in the base plate with the spring engaged against the opposite end of the rocker member, substantially as described. 105

10. In a latch, a housing having an elongated opening, a latch lever pivoted within the housing and projecting through said opening and adapted to swing both ways from a central normal position, a transpos- 110

able abutment associated with said housing and adapted to be located at either side of said lever for the purpose of preventing movement of said lever in one direction from central normal position.

11. In a latch, a housing having an elongated opening, a latch lever pivoted within the housing and projecting through said opening and adapted to swing both ways from a central normal position, a transposable abutment associated with said housing and adapted to be located at either side of said lever for the purpose of preventing movement of said lever in one direction from central normal position and spring means acting upon said lever to move it into engagement with said abutment.
12. In a latch, a housing having an elongated opening, a latch lever pivoted within the housing and projecting through said opening and adapted to swing both ways from a central normal position, a transposable abutment associated with said housing and adapted to be located at either side of said lever for the purpose of preventing movement of said lever in one direction from

central normal position, and spring means associated with said lever and said abutment to retain said abutment in place and to swing the lever into engagement with the abutment.

13. In a latch, a housing having an elongated opening, a latch lever pivoted within the housing and projecting through said opening and adapted to swing both ways from a central normal position, a detent on the housing engageable with said lever to retain the lever when swung in either direction from central normal position, a transposable abutment associated with said housing and adapted to be located at either side of said lever for the purpose of preventing movement of said lever in one direction from central normal position, and spring means associated with said lever and said abutment to retain said abutment in place and to move the lever into engagement with the abutment.

In testimony whereof we affix our signatures.

ALEXANDER F. WINTERS.
BASIL R. CRAMPTON.
